US0D1003916S

(12) **United States Design Patent** (10) Patent No.: **US D1,003,916 S**
(45) Date of Patent: ** Nov. 7, 2023

(54) **DISPLAY SCREEN WITH GRAPHICAL USER INTERFACE**

(71) Applicant: **FANUC CORPORATION**, Yamanashi (JP)

(72) Inventor: **Shinichi Ozeki**, Yamanashi (JP)

(73) Assignee: **FANUC CORPORATION**, Yamanashi (JP)

(**) Term: **15 Years**

(21) Appl. No.: **29/806,418**

(22) Filed: **Sep. 2, 2021**

(30) **Foreign Application Priority Data**

Mar. 4, 2021 (JP) ..... 2021-004530 D

(51) **LOC (14) Cl.** **14-04**

(52) **U.S. Cl.**

USPC **D14/488**

(58) **Field of Classification Search**

(57) **CLAIM**

The ornamental design for a display screen with graphical user interface, as shown and described.

DESCRIPTION

The FIGURE is a front view a display screen with graphical user interface showing my new design;

The outermost broken lines illustrate a display screen and form no part of the claimed design. The remaining broken lines, including broken line Japanese characters, illustrate portions of the graphical user interface that form no part of the claimed design.

1 Claim, 1 Drawing Sheet
